UNITED STATES PATENT OFFICE.

CHARLES E. GOSSETT, OF ELDON, MISSOURI, ASSIGNOR TO THE INGOLDSBY AUTOMATIC CAR COMPANY, OF ST. LOUIS, MISSOURI, A CORPORATION OF WEST VIRGINIA.

DUMP-CAR.

No. 861,721.

Specification of Letters Patent.

Patented July 30, 1907.

Application filed October 27, 1906. Serial No. 340,819.

To all whom it may concern:

Be it known that I, CHARLES E. GOSSETT, a citizen of the United States, residing at Eldon, in the county of Miller and State of Missouri, have invented a certain new and useful Improvement in Dump-Cars, of which the following is a full, clear, and exact description, reference being had to the accompanying drawings.

This invention relates to means for directing the discharge from dump cars. It is especially well adapted for cars of the Ingoldsby type, wherein there is a central longitudinal beam to which are hinged dumping doors which swing downward at their outer edges at the sides of the car. With such car my invention is most satisfactorily embodied in a baffle structure depending from the side of the car and adapted to deflect the falling material. With such an arrangement the car is especially well adapted for ballast service, as the baffle prevents the ballast going over the edge of the railway embankment and insures it being deposited immediately alongside the rail.

The invention is hereinafter more fully described and its essential characteristics set out in the claims.

In the drawings, Figure 1 is a side elevation of an Ingoldsby car equipped with my baffle; Fig. 2 is a cross section of such car, and Figs. 3 and 4 are details showing means for securing the baffle to the side of a steel car.

Referring by reference letters to the drawings, A represents the sides of the car; B the central longitudinal beam; C the dumping doors which are hinged at their inner edges to such beam, and at their outer edges are adapted to abut the lower edges of the sides. The doors are shown as adapted to be held in a closed position by means of hooks D on the sides of the car engaging floor beams E projecting from the undersides of the doors. A link F connects the hooks D with an operating lever G. On the underside of the longitudinal beam I have shown a depending plate H which carries arc-shaped bumpers J which are adapted to be locked with their ends projecting varying amounts, thus holding the doors in the desired position when dropped. Suitable springs K are carried on the undersides of the doors to engage the bumpers. End shields L are provided to prevent the material passing off the ends of the doors. This much of the construction is usual in Ingoldsby cars.

The baffle board, which may be made of either wood or metal, is designated N. It depends from the car side, being carried by suitable hangers P. As shown in the drawing, the hangers are arranged to hold the baffle board in a position outside of the plane of the car side. This allows clearance for the projecting floor beams E, and has been found satisfactory in causing the desired deflection of the discharged material.

As shown in Figs. 1 and 2, where a wooden car is illustrated, the hanger P is bolted rigidly to the lower chord of the car side by bolts Q, the hanger consisting of a continuous off-set strap. The baffle board in these figures is composed of a plurality of longitudinal planks bolted to the outer side of the hangers.

In Fig. 3, the baffle is illustrated as applied to a steel car. Here the car side A has a lower chord a in the form of an angle beam with an outwardly projecting horizontal flange a'. The hanger P has an inwardly bent portion p at its upper end. The inwardly bent portion or flange is shown as resting on the flange a', the hanger being secured thereto by a pin R projecting through the two flanges and provided with a suitable cotter r. In Fig. 4 a steel car side with a similar lower chord is shown; the hanger P is also similar. In this instance, however, the hanger flange is shown as lying on the underside of the flange a' of the chord, being rigidly secured thereto by a bolt R' passing through the flanges and provided with a nut r'.

The various forms shown in the drawings are to be taken not as an enumeration of modifications covered, but as illustrating the fact that my baffle may be constricted in a variety of manners and secured to the car side in a variety of ways. The constructions shown, it is to be noticed, are very simple and cheap, while they operate to effectively hold a deflecting surface at the desired location.

I claim.

1. The combination of a side dumping car having a door adapted to support the load and adapted to drop, and a baffle depending from the side of the car and adapted to deflect the material dumped.

2. The combination of a dump car having suitable means for discharging the load outside of the rail, and means independent of the support of the load in the car carried by the side of the car for deflecting the material so discharged therefrom.

3. A dump car having a door adapted to support the load and swing to discharge the load outside of the rail, combined with a baffle located adjacent to the discharge opening and adapted to deflect the discharged load, while allowing it to discharge outside of the rail.

4. The combination of a dump car having a load supporting door forming a portion of the floor of the car and adapted to drop at one edge to discharge the load across the door, and a baffle located opposite the path through which the free edge of the door swings in dropping, whereby the discharged load may impinge on said baffle and be deflected thereby.

5. The combination of a dump car having a longitudinal door, the free edge of which is adapted to swing downward at the side of the car to discharge the load toward the side, and a baffle carried by the side to receive and deflect such discharge.

6. The combination of a side-dumping car and a baffle carried by the side of the car and adapted to deflect the material dumped, said baffle being located in a plane outside of the plane of the car side.

7. The combination of a car having a central longitudi-

- nal beam, dumping doors hinged to the opposite edges of said beam and having their free edges adapted to coöperate with the car sides and swing downward to discharge the load outwardly, and a pair of baffles depending from the 5 car sides and adapted to deflect the discharged load.
8. The combination of a side dumping car, a baffle for each side, and hangers secured to the baffles, and to the corresponding sides and holding the baffles opposite the discharge openings.
10. 9. The combination of a car having a central longitudinal beam, dumping doors hinged to the opposite edges of said beam and having their free edges adapted to coöperate with the car sides and swing downward to discharge the load outwardly, baffles, and hangers secured to the baffles 15 and to the corresponding side, whereby the baffle stands opposite the sidewise discharge opening of the door.
10. The combination of a side-dumping car, hangers secured to the sides thereof and depending therefrom in planes which are outside of the plane of the side walls of the car, and baffles secured to said hangers.
- 20 11. The combination with the side walls of side-dumping cars, of hangers rigidly secured thereto and depending in planes outside of the planes of the car sides and baffles extending lengthwise of the car and secured to said 25 hangers.
12. The combination of a side-dumping car having hinged doors which form a portion of the load carrying floor and are adapted to swing downward at their outer edges to discharge beneath the car side, bumpers for said
- doors to hold them when dropped in such discharging position, and baffles carried by the sides in the path of the discharging material.
13. The combination of a side-dumping car having hinged doors which form a portion of the load carrying floor and are adapted to swing downward at their outer edges to discharge beneath the car side, means for holding said doors when dropped in such discharging position, and vertical baffles rigidly carried by the car sides in the path of the discharging material but beyond the doors, said baffles receiving the discharge by momentum and causing 40 its deposit outside of the rails.
14. The combination of a side-dumping car whose sides have lower chords, depending hangers carried by such chords longitudinally extending baffles carried by such hangers, and dumping doors adapted to discharge their 45 material against such baffles.
15. The combination of a side-dumping car having a door adapted to support the load and adapted to drop to discharge its load outside of the rail, and a baffle located outside of the vertical plane through the rail and adapted to deflect the load after it has passed beyond the rail.

In testimony whereof, I hereunto affix my signature in the presence of two witnesses.

CHARLES E. GOSSETT,

Witnesses:

CHAS. H. MEYER,

MARY D. WHITCOMB.
